DESIGN FOR A LAMP REFLECTOR

Edward Herst, San Francisco, Calif.

Application May 15, 1934, Serial No. 51,798

Term of patent 3½ years

To all whom it may concern:

Be it known that I, EDWARD HERST, a citizen of the United States, residing in the city and county of San Francisco, State of California, have invented a new, original, and ornamental Design for a Lamp Reflector, of which the following is a specification, reference being had to the accompanying drawing, forming part thereof.

Referring to the drawing:

Fig. 1 is a plan of a lamp reflector, showing my new design.

Fig. 2 is a side elevation of the lamp reflector of my design.

Fig. 3 is a side elevation similar to Fig. 2 but at 90° therefrom, showing the lamp reflector of my design.

Fig. 4 is a bottom view of the lamp reflector of my design.

I claim:

The ornamental design for a lamp reflector, as shown.

EDWARD HERST.
